UNITED STATES PATENT OFFICE.

FAY T. RODGERS, OF MEMPHIS, TENNESSEE.

REFRIGERATING APPLIANCE.

Application filed February 11, 1924. Serial No. 692,004.

To all whom it may concern:

Be it known that I, FAY T. RODGERS, a citizen of the United States, residing at Memphis, in the county of Shelby and State 5 of Tenn. aforesaid, have invented certain new and useful Improvements in Refrigerating Appliances, of which the following is a full, clear, and exact description such as will enable anyone skilled in the art to make and 10 use the same.

My invention relates to refrigerant container adapted for use in refrigerators, particularly those of the cabinet display type in which a portion of the interior of the 15 refrigerator, or refrigeration chamber, is used for holding goods which are to be kept cool, and the balance of the chamber is adapted to contain a refrigerating member or members, which members are preferably removable and disposed at the ends of the chamber. 20

The object of my invention is to provide a simple, inexpensive and efficient refrigerating member which will effectually promote circulation of the air into contact with a cooling medium and thereby thoroughly chill the same and deliver it to the storage compartment in the most efficient manner. 25

In carrying out this object I propose to 30 employ as a refrigerant member a container or tank which is adapted to hold a mixture preferably of cracked ice and salt, which produces as is well known, a much lower temperature than could be obtained by ice 35 alone and to provide means for causing air to circulate through such container in a manner to secure a thorough chilling of the air.

With this object in view the invention 40 comprises the novel features of construction hereinafter more fully set out in the drawings, specification and claims.

In the drawings:

Fig. 1 is a vertical longitudinal section of 45 a device constructed in accordance with my invention.

Fig. 2 is a sectional plan of the device taken on the line II—II of Fig. 1.

Fig. 3 is a vertical section of the device 50 on the line III—III of Figs. 1 and 2 on approximately double the scale of Figs. 1 and 2.

Fig. 4 is an enlarged vertical section of 55 the container or tank shown in Fig. 1, taken on the line IV—IV of Fig. 3.

Referring now to the drawings in which

the various parts are referred to by numerals, 1 designates the casing of a refrigerator of the cabinet type including the usual top 2, bottom 3, ends 4, front 5 and back 6. 60 The front 5 is preferably formed with glass panels whereby the goods disposed within the refrigeration chamber are displayed and the back 6 is provided with doors 7 and 8 through which the refrigerant members and 65 the goods to be displayed within the cabinet may be placed therein or removed therefrom, or through which access may be had to the interior of the refrigerator for cleaning or other purposes. 70

9 are brine trays adapted to receive the drip from the refrigerant members 10. 11 are drip pipes leading from the refrigerant tanks 10 and emptying into the brine trays 9 which drip pipes may be shut off by valves 75 12 when it is desired to remove the refrigerant tanks. 13 is a drip pipe into which the brine trays 9 discharge.

The refrigerant members 10 are preferably rectangular tanks of metal having bottoms 14, fronts 15, a back 16 and sides 17 and 18. 19 is a handle fastened to the back 16 to provide means for removing the tank for refilling. The tank may be provided with a top 20 which lies thereover, but which is not fastened thereto, or if desired, may be left open. 80

Within each of these tanks are U shaped tubes each preferably of one piece construction, and each comprising an upper leg 21, 90 a lower leg 22 and a vertical connecting leg 23. The upper and lower legs 21 and 22 have open ends which project through and are securely sealed to the side 17, the open end of the leg 21 being substantially vertically above the open end of the leg 22. The leg 21 extends inward from the side 17 in a horizontal direction but inclined slightly downward therefrom, thence curves into the vertical section 23, which in turn curves 100 outward into the lower section 22 which inclines downward from the horizontal, and which extends from the vertical section 23 through the side 17 and terminates as before stated in an open end. The open ends of these sections 21 and 22 being sealed to the side 17 by brazing or in such other suitable manner as may be desired. The body of the U shaped tube including the vertical section 23 thereof is entirely within the tank 10 and is spaced away from the side 18 so

that a space is provided between the said 105

110

side 18 and the tube which may be filled with ice and salt for refrigerating purposes, and permitting the entire body of the tube to be surrounded by the refrigerating material. 24 are spacing members which secure the vertical leg 23 to the side 18 and hold it properly spaced therefrom. There may be one, two, or even more of these U shaped tubes within the tank 10, preferably 10 two only being used.

Immediately beneath the lower end of each of the upper legs 21 of the tubes is a short deflecting shelf 25 which directs the current of air toward the mouth of the tube. 15 The general direction of the circulation of air through these tubes is shown by the arrows on the drawing. The warmer air in the top of the refrigerator passes into the upper leg 21 and as it is cooled by the ice and salt 26 becomes heavier and drops downward through the vertical section and thence outward through the lower leg 22.

It will be especially noted that in this device I have provided a smooth and uninterrupted channel which is of the type best suited to take advantage of the slight difference in specific gravity caused by the cooling of the air within the refrigerant tank and that I thereby secure the maximum 25 air circulation possible in such a tank.

Having now fully described my invention, what I claim and desire to secure by Letters Patent of the United States is: -

1. A refrigerant container, comprising a

tank having therein air-circulation tubes of 35 one-piece construction, each formed in substantially U shape, with curvilinear bends, the legs of the U being spread apart, and both ends of the tube being secured to the same side wall of the tank, in position for 40 the openings in said ends to register with openings near the top and the bottom, respectively, of said wall, whereby air passing through the tube from its upper to its lower end moves downward at all points in its 45 travel, and a member securing each of the said bends in spaced relation to the contiguous side wall of said tank.

2. A refrigerant container, comprising a tank having therein air-circulation tubes of 50 curvilinear cross-section, each formed in substantially U shape, with curvilinear bends, the legs of the U being spread apart, and both ends of the tube being secured to the same side wall of the tank, in position 55 for the openings in said ends to register with openings near the top and the bottom, respectively, of said wall, whereby air passing through the tube from its upper to its lower end moves downward at all points in 60 its travel, and an air-intake deflector adjacent the upper end of each of said tubes.

In testimony whereof I have hereunto set my name.

FAY T. RODGERS.
